United States Patent Office

Des. 212,663
Patented Nov. 5, 1968

212,663

EXPANDABLE CARRYING BAG

Anthony N. D'Elia, Riverdale, and Edward M. Stolarz,
Yorktown Heights, N.Y., assignors to Reliable Luggage
Incorporated, West Pittsburg, Pa., a corporation of Pennsylvania

Filed Dec. 20, 1967, Ser. No. 9,865

Term of patent 14 years

(Cl. D87—3)

FIG. 1

FIG. 2

FIG. 3

FIG. 4

FIG. 5

FIG. 6

FIG. 1 is a front elevational view of an expandable carrying bag embodying our new design;

FIG. 2 is a rear elevational view thereof;

FIG. 3 is a side elevational view thereof;

FIG. 4 is a side elevational view of the opposite side of that shown in FIG. 3;

FIG. 5 is a top plan view thereof; and

FIG. 6 is a bottom plan view thereof.

We claim:

The ornamental design for an expandable carrying bag, as shown.
